US0D1100227S

(12) **United States Design Patent** (10) Patent No.: **US D1,100,227 S**
Tan (45) Date of Patent: ** Oct. 28, 2025

(54) **ELECTRODE HEAD OF THE SKIN TREATMENT DEVICE**

(71) Applicant: **Shenzhen Ulike Smart Electronics Co., Ltd.**, Shenzhen (CN)

(72) Inventor: **Lijun Tan**, Shenzhen (CN)

(73) Assignee: **Shenzhen Ulike Smart Electronics Co., Ltd.**, Shenzhen (CN)

(**) Term: **15 Years**

(21) Appl. No.: **29/934,752**

(22) Filed: **Mar. 27, 2024**

(51) LOC (15) Cl. **24-01**

(52) U.S. Cl.

USPC **D24/209**; D24/200

CLAIM

The ornamental design for the electrode head of the skin treatment device, as shown and described.

DESCRIPTION

FIG. 1 is a front perspective view of the electrode head of the skin treatment device, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the electrode head of the skin treatment device, which form no part of the claimed design.

1 Claim, 8 Drawing Sheets
